UNITED STATES PATENT OFFICE.

CARL E. SWENSON, OF ROCKFORD, ILLINOIS, ASSIGNOR TO MECHANICS MACHINE CO.,
OF ROCKFORD, ILLINOIS.

CLUTCH.

1,162,115.

Specification of Letters Patent. Patented Nov. 30, 1915.

Application filed February 11, 1915. Serial No. 7,574.

To all whom it may concern:

Be it known that I, CARL E. SWENSON, a citizen of the United States, residing at Rockford, in the county of Winnebago 5 and State of Illinois, have invented certain new and useful Improvements in Clutches; and I do declare the following to be a full, clear, and exact description of the invention, such as will enable others skilled in the art 10 to which it appertains to make and use the same.

My invention relates to improvements in clutches and more particularly to those designed for use in connection with unitary 15 transmission systems, such as those used most commonly on automobiles, although it will be evident that the application of the invention need not be limited in this respect.

The object of the invention is to improve 20 upon the general construction of devices of this character to such an extent as to provide a clutch which will be much more efficient than the common type of clutch now in use for the above named purpose.

To this end, I employ certain novel features of construction and combination hereinafter described and claimed and shown in 25 the accompanying drawings wherein:

Figure 1 is a vertical longitudinal section of a clutch constructed in accordance 30 with my invention; Figs. 2 and 3 are vertical transverse sections as seen on the planes indicated by the lines 2-2 and 3-3 of Fig. 1; Fig. 4 is a detail vertical longitudinal 35 section taken along the plane indicated by the line 4-4 of Fig. 2.

In these drawings constituting a part of 40 the application, the numeral 1 designates the circular rim of a common type of fly wheel which is provided on its inner side with a friction ring 2, a web 3 being shown as continuing inwardly and longitudinally from the inner edge of the ring and as being secured by an appropriate coupling 45 to the engine shaft 5.

Secured to one edge of the rim 1, by machine screws 6 or other appropriate fasteners, is an end plate 7 which, for the sake of lightness is preferably provided with a number 50 of openings 8, while its center is offset in the opposite direction from the web 3, is provided with an internal annular seat 9 and with an opening 10, the latter being disposed at the axis of said plate.

Projecting axially through the opening 10, 55 and having a bearing stud 11 on its inner end revolvably mounted in a bearing 12 disposed at the center of the web 3, is a second shaft section 13 whose inner end portion is provided with a plurality of longitudinally extending keys 14 upon which a hub member 15 is mounted to slide longitudinally of the shaft 13. Secured by rivets 16 or other appropriate fasteners to the hub member 15, is a disk 17, the edge of this 60 disk being disposed contiguous to the active face of the ring 2, but being spaced therefrom by a flat ring 18 which may be formed of any friction creating material.

Coacting with the disk 17 is a movable 70 member or clutch ring 19 which is spaced from said disk by a ring 20 similar to the ring 18 previously mentioned. This ring 19 is here shown as provided, at circumferentially spaced points, with a plurality of 75 bosses 21 which extend from said ring toward the end plate 7, these bosses being provided for the anchorage of the inner ends of a plurality of rigid pins 22 (see more particularly Figs. 1 and 4). The pins 22 lie 80 parallel to the shaft 13 and project through guide bosses 23 which are disposed at suitably spaced points upon the end plate 7, the outer ends of said pins being provided with stops 24 between which and the guides, 85 coiled springs 25 are interposed. It will therefore be evident that as the end plate 7 is rotated by rotation of the fly wheel, the pins 22 will impart such rotary movement to the ring 19. Furthermore, it will be clear 90 that the tension of the springs 25 is exerted to move said ring 19 normally away from the disk 17. For the purpose of forcing said ring toward said disk, however, a plurality 95 of ring actuating levers 30 is provided, these levers being radially disposed as clearly shown in Figs. 1, 2 and 3 of the drawings and being pivotally supported at 31 upon circumferentially extending pins which pass through ears 32 projecting longitudinally 100 from the ring 19 toward the end plate 7. By reference more particularly to Fig. 1, it will be seen that the pivots 31 are very near the outer ends of the levers 30, and that said outer ends, designated in the drawings by the numerals 33, are disposed in contact with the inner ends of a plurality of set screws 34 which are threaded through 105

the end plate 7 and locked by the provision of nuts 35. By this formation, since the set screws 34 constitute the fulcrums around which the levers 30 are to be rocked, it is 5 evident that adjustable fulcrums are provided for said levers, this being an important feature, since as the friction rings 18 and 20 become worn, and it is necessary to force the ring 19 farther toward the disk 17, 10 the fulcrums may be adjusted to accomplish this result without causing the levers 30 to move excessively inward.

Heretofore, it has been common practice to provide grooved rings for the reception 15 of the inner ends of the levers 30 and to employ spring means for forcing said rings inwardly, thus rocking the levers around their fulcrums to move the ring 19 toward the ring 2, thus clamping the disk 17 therebetween and imparting rotary movement to 20 the shaft 13. This construction, however, has been found to be inadequate since, as may result from faulty construction or from numerous other causes, inward movement of 25 all of the levers to the same extent, will not effect the same clamping action on all parts of the disk 17. It therefore becomes expedient to so mount the aforesaid levers 30 as to allow them to be moved inwardly independent 30 of each other, thus allowing them to be disposed to their limits of movement, regardless of each other. For accomplishing this result, the inner ends of all of the levers 30 are free to move inwardly to the necessary 35 extent, and the inner end of the usual conical coiled spring 40 is disposed directly in contact with said inner ends as shown in Fig. 1, the outer end of said spring being located in the seat 9 before described. By 40 this change in construction, it will be evident that the tension of the spring is exerted upon the individual levers to actuate them independently of each other, thus allowing said levers to be moved inwardly to their 45 limits of movement, irrespectively of the movement of each other. By so doing, the clamping action exerted upon the outer edge portion of the disk 17 may be equalized at all points.

50 In order to dispose the levers 30 to inactive position, thus allowing the springs 25 to return the ring 19 to its normal position, and throw the clutch out of action, a sleeve 45 is preferably provided, such sleeve 55 rounding the shaft 13 and having its inner end mounted slidably upon the hub 15, said inner end being provided with a laterally extending flange 46 which abuts the inner edges of the levers 30, while the outer end of 60 said sleeve is provided with a longitudinally shiftable thrust bearing 47 which may be moved outwardly by an appropriate crank 48, thereby moving the levers 30 to their inoperative positions and throwing the clutch 65 out of action.

By summarizing the numerous features before described, it will be evident that the ring 2 and web 3 constitute one end wall of a cylindrical casing, that the rim 1 becomes in effect the annular wall of such casing, 70 and that the end plate 7 constitutes the remaining end wall thereof. Furthermore, although the disk 17 may slide to a predetermined extent upon the shaft 13, it becomes in effect, a relatively fixed clutch 75 member against which the ring 19, or the relatively movable clutch member, is to be forced. Similarly, it will be observed by those skilled in the art to which the invention relates that although a single coiled 80 spring 40 has been shown for disposing the clutch actuating levers 30 to active position, other spring means might well be provided for this purpose, the salient feature being that the levers 30 may be moved independently of each other and that the spring means is so disposed as to effect this movement.

Furthermore, although I preferably provide a ring 19 to be carried by the casing 90 above described and to be returned to normal position by the springs 25, it clearly lies within the scope of the present invention to replace said ring by any appropriate type of clutch member, and to mount the 95 same upon any preferred design of rotating member, in the specific manner before set forth, namely by providing the pins 22, stops 24, and springs 25. It will likewise be apparent, that although one specific mounting 100 of the levers 30 is disclosed in the drawing, and the preferred type of adjustable fulcrum, that these features could well be altered without departing from the spirit of the invention as claimed. 105

I claim:

1. The combination with a rotating body having a plurality of circumferentially spaced guides whose axes lie parallel to the axis of said body, clutch members contiguous to said body, means for forcing one of said members into engagement with the other, of a plurality of rigid pins projecting laterally from one of said clutch members and extending through the guides in said body, stops on the free ends of said pins, and springs interposed between the guides and the stops. 110

2. The combination with a cylindrical casing and means to rotate the same, a shaft 120 projecting axially into said casing through one end thereof, a clutch member non-rotatably mounted on said shaft and disposed in the casing, a movable clutch ring in said casing, and means to force the ring into contact with the clutch member, of a plurality of rigid pins projecting longitudinally from the ring through one end wall of the casing and having stops on their outer ends, and ring retracting springs interposed between 125 130

said stops and said end wall to retain the ring out of engagement with the clutch member.

3. The combination with a clutch including a plurality of clutch applying levers, of a coiled spring having one of its ends in direct contact with one end of said levers whereby to move the same independently.

In testimony whereof I have hereunto set my hand in presence of two subscribing witnesses. 10

CARL E. SWENSON.
